UNITED STATES PATENT OFFICE.

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 13, 1927. Serial No. 191,059.

My invention relates to railway traffic controlling apparatus, and particularly to apparatus of the type comprising train-carried governing means controlled by train governing energy received from the trackway. More particularly my present invention relates to the trackway portion of such apparatus.

The present application is an improvement on the apparatus disclosed and claimed in my co-pending application filed August 11, 1926, Serial No. 128,594, for railway traffic controlling apparatus.

I will describe one form of trackway apparatus embodying my invention, and will then point out the novel features thereof in claims.

In the accompanying drawings, Figs. 1 and 2 are diagrammatic views, which, when placed end to end with Fig. 1 on the left, illustrate one form of trackway apparatus embodying my invention. These views are further so arranged that they constitute one complete unit of a system, so that the left-hand end of Fig. 1 is a continuation of the right-hand end of Fig. 2.

Referring to the drawings, the reference characters 1 and 1^a designate the track rails of a stretch of railway track over which traffic moves in both directions, and the reference characters 4 and 4^a designate the track rails of a passing siding, a series of which are usually located at convenient intervals in a stretch of single track. The track rails 1 and 1^a are divided by insulated joints 2 to form a plurality of blocks A—B, B—C, C—D and D—A, and the block A—B is further divided into two sub-blocks A—E and E—B.

Traffic through the stretch shown in the drawing is governed by wayside signals, each of which is designated by the reference character S with a suitable exponent. It will be noted that two opposing signals are located at the point A and that two opposing signals are located at the point D, but that an eastbound signal S^B is located at the point B and a westbound signal S^C is located at the point C. All of the signals are

controlled in accordance with what is known in the railway signaling art as absolute permissive block signaling. That is to say, when an eastbound train enters section A—B, it places the westbound signals S^A_W, S^C and S^D_W at stop, and each of these signals remains at stop until the train has passed it; as the train passes signal S^A_E, it places this signal at stop, and as the train passes signal S^B it places the latter signal at stop, but signal S^A_E then moves to the caution position. When the train passes signal S^D_E, it places the latter signal at stop, whereupon signal S^B moves to the caution position and signal S^A_E moves to the proceed position. The apparatus for controlling these signals is omitted from the drawing, with the exception of the line relays each of which is designated by the reference character H with an exponent corresponding to that of the associated signal. The operation of the signals during the westbound movement is, of course, similar to the operation just explained for an eastbound movement.

Located immediately in the rear of the eastbound signal S^B is a short insulated section of track which is known as the eastbound "reset" section, and located immediately in the rear of westbound signal S^C is a similar westbound reset section X¹—C. Each of these sections will usually be about 200 feet in length. Location A is provided with a pair of reset sections X¹—A and A—X², each of which is preferably about 100 feet in length, and location D is provided with a similar pair of reset sections X⁵—D and D—X⁶. Each reset section is provided with an alternating current track circuit which is normally supplied with current from the secondary 6 or 7 of a transformer designated by the reference character T with an exponent corresponding to the location. Considering reset section X¹—A, for example, the right-hand terminal of secondary 7 of transformer T^A is connected through a reactance 10 and wire 11 with rail 1^a at the right-hand end of the section, and the left-hand terminal of this

secondary is connected by wire 25 with rail 1 at the left-hand end of the section. A detector relay E^A_E has one of its terminals connected with rail 1^a at the left-hand end of 5 the reset section through wires 12 and 112, while the other terminal of this relay is connected with rail 1 at the right-hand end of the reset section through wires 24 and 113. In the form here shown, the detector relay 10 is of the direct current type, and an asymmetric unit 114 is interposed between one terminal of the relay and one of the track rails so that the relay receives pulsating direct current. The track circuit for each of 15 the remaining reset sections is similar to the circuit for section X¹—A. The primary 5 of each transformer T is connected with the secondary 8 of a line transformer designated by the reference character L with an exponent corresponding to the location, and the primary 9 of each transformer L is constantly supplied with alternating current from a source not shown in the drawing. It will be noted that the primary 5 of each 20 transformer T^A and T^D is constantly connected with the secondary 8 of the associated transformer L, whereas the primary 5 of each transformer T^B and T^C is connected with secondary 8 of the associated transformer L through back contacts 54 and 55 of a relay Q^B or Q^C. The control and the function of the relays Q will be explained hereinafter.

Each block and sub-block is provided with 35 a track circuit comprising a track battery 3, and a track relay designated by the reference character F with a distinguishing exponent. Each block B—C and C—D is provided with two of these track relays located at the two ends of the block respectively, and the track battery 3 for each of these blocks is located at the middle of the block.

Each block and each sub-block is further 45 supplied at times with alternating train governing current under the control of traffic conditions in advance, and this current is supplied from the transformers T through the rails of the reset sections, so that in the 50 event of failure of the supply of alternating current to any reset section, the supply of train governing current to the block or sub-block in the rear of such section will also be discontinued.

55 Before explaining the operation of the apparatus, it should be pointed out that the apparatus herein shown and described is suitable for co-operation with train-carried governing means requiring the supply of alternating train governing current to at least one of the track rails to prevent a stop indication of any suitable type such as an automatic application of the brakes. If the supply of such current is discontinued, a stop 60 indication will result unless the engineman

takes proper steps to acknowledge the change in traffic conditions. If he does acknowledge, the train may proceed without incurring a stop indication, but if alternating current is again supplied to the rails occupied 70 by the train and this current is subsequently discontinued, the engineman must again acknowledge to prevent a stop indication. One form of train-carried governing means suitable for co-operation with the trackway apparatus herein disclosed, is shown and described in United States Letters Patent Reissue No. 16,502, granted on December 7, 1926, to Ronald A. McCann, for railway traffic controlling apparatus, 75 80

In apparatus of the type described in that patent, the train-carried governing means is controlled by alternating current in the track rails through the medium of an inductive receiver carried on the train in advance of the forward axle, so that it is necessary for the alternating train governing current to flow through at least one track rail in advance of the train. 85

The operation of the apparatus is as follows: I will first assume that an eastbound train occupies block D—A, so that track relay F⁷ is open. This will cause line relays H^A_w and H^D_E to be open, so that signals S^A_w and S^D_E will indicate stop. Alternating train governing current will then be supplied to the rails of section D—A through a circuit which passes from secondary 7 of transformer T^A, through reactance 10, wire 11, rail 1^a of reset section X¹—A, wires 12, 13, 14 and 15, reactance 16, rail 1, the wheels and axles of the train in block D—A rail 1^a, resistance 17, track battery 3, wire 18, circuit controller 19 operated by signal S^A_w, wire 20, circuit controller 21 operated by signal S^A_E, front contact 22 of line relay H^A_E, wires 23 and 24, rail 1 of reset section X¹—A, and wire 25 to secondary 7. It will be seen 90 95 100 105 110 115 120 125 130

that this circuit will not be closed unless signal S^A_w is at stop, signal S^A_E indicates proceed or caution, and relay H^A_E is closed. As the train enters reset section X¹—A, it will receive alternating train governing current from rail 1^a, and the voltage supplied to this section is such as to effectively operate the train-carried governing mechanism to prevent a stop indication. While the train occupies reset section A—X², it will receive alternating current from rail 1, and so a stop indication will still be prevented. As the train enters reset section A—X² it will place signal S^A_E at stop, and it will also place opposing signals S^C and S^D_w at stop, these signal operations being primarily due to the opening of relay E^A_w.

When the train passes point X², it will receive train governing current in the following manner: The current from secondary 6 of transformer T^B will flow through reactance 26, wire 27, rail 1^a of reset section

X^a—B, wires 28, 29 and 30, primary 40 of a transformer **P^B**, wire 31, front contact 32 of track relay **F²**, wire 33, circuit controller 34 operated by signal **S^B**, front contact 35 of line relay **H^B**, wire 36, back contact 37 of an auxiliary relay **K^B**, wire 38, rail 1 of reset section **X^a**—B, and wire 39 to secondary 6 of transformer **T^B**. The secondary circuit for transformer **P^B** is from secondary 41, through wire 42, primary 43 of a transformer **G¹**, wire 44, common wire **U**, and wires 45, 46, 47 and 48 to secondary 41. Secondary 49 of transformer **G¹** is connected across the rails at the right-hand end of section **X^a**—E in series with the track battery 3. When the train enters section **E**—**X^a**, it will receive train-carried governing current by virtue of a circuit which passes from secondary 6 of transformer **T^B**, through rail 1^a of reset section **X^a**—B, wires 28, 29 and 50, resistance 51, wire 52, rail 1, the wheels and axles of the train, rail 1^a, wire 53, back contact 32 of track relay **F²**, wire 33, circuit controller 34, front contact 35 of relay **H^B**, wire 36, back contact 37 of relay **K^B**, wire 38 rail 1, and wire 39 to secondary 6.

The relay **K^B** is connected with the circuit for line relay **H^C**, and a portion of this circuit is shown in the drawing, such portion being wire 115, front contact 116 of track relay **F²**, wire 117, and contact 118 of checking relay **E^B**. One terminal of relay **K^B** is connected with wire 117, and the other terminal is connected through wires 119 and 45 with common wire **U**. Since relay **H^C** is controlled by all track relays between signals **S^A**—**E** and **S^C**, and since relay **K^B** is tapped onto the control circuit for relay **H^C** at point B, it follows that relay **K^B** is controlled by all track relays between A and B and consequently is opened by the eastbound train when the train passes point A.

When the eastbound train enters reset section **X^a**—B, it will receive train governing current from secondary 6 of transformer **T^B**, through rail 1^a, it being understood that relay **Q^B** remains open during the passage of an eastbound train.

When the train enters section B—C, it will receive train governing current in the following manner: If signal **S^D**—**E** is in the clear or caution position, current will flow from secondary 6 of transformer **T^D**, through reaction 57, rail 1^a of reset section **X^a**—D, wires 58, 59 and 60, primary 61 of a transformer **P^D**, wire 62, front contact 63 of track relay **F⁶**, wire 64, circuit controller 65 operated by signal **S^D**—**W**, wire 66, circuit controller 67 operated by signal **S^D**—**E**, front contact 68 of relay **H^D**, wires 69 and 70, rail 1 of section **X^a**—D and wire 71 to secondary 6 of transformer **T^D**. It follows that the train will not receive train governing current unless signal **S^D**—**E** is in the proceed or caution position and the circuit for the reset section **X^a**—D is intact.

As the train passes through reset sections **X^a**—D and D—**X^a**, it will receive train governing current from secondaries 6 and 7, respectively, of transformer **T^D**. When the train enters section **X^a**—E, signal **S^B** is in the stop position so that the supply of

primary 79 of transformer **G⁴**, wires 80 and 81, common return wire **U**, and wire 82 to secondary 72. The secondary 120 of transformer **G⁴** is connected across the rails of block B—C. When the train enters the westbound reset section C—**X^a**, it will open checking relay **E^C**, and while track relay **F⁴** is still open a pick-up circuit for relay **Q^C** will be closed, which circuit is from terminal Z of a suitable source of current through back contact 91 of line relay **H^C**, back contact 93 of track relay **F⁴**, wire 94, back contact 95 of relay **E^C**, wire 96, front contact 97 of relay **K^C**, winding of relay **Q^C**, wires 98 and 81 and common wire **U** to terminal O of the same source of current. Relay **Q^C** will remain closed as long as any part of the train occupies reset section C—**X^a**, because this relay is provided with a stick circuit which passes from terminal Z, through back contact 99 of relay **E^C**, wire 100, front contact 56 of relay **Q^C**, wire 101, winding of relay **Q^C**, and wires 98, 81 and **U** to terminal O. While relay **Q^C** is closed, the supply of current to transformer **T^C** from transformer **L^C** is discontinued, and current is then supplied to transformer **T^C** from secondary 72 of transformer **P^D**, the circuit being from secondary 72, through wire 73, contact 74 of track relay **F⁵**, wires 75 and 83, front contact 55 of relay **Q^C**, wire 84, primary 5 of transformer **T^C**, wire 85, front contact 54 of relay **Q^C**, and wires 86, 81, **U**, and 82 to secondary 72 of transformer **P^D**. Inasmuch as the supply of current to transformer **P^D** depends upon the position of signal **S^D**—**E**, it will be seen that during the passage of an eastbound train through the westbound reset section C—**X^a**, the supply of train governing current to this train will depend upon traffic conditions in advance.

While the train occupies the section **X^a**—**X^a**, it is supplied with train governing current from secondary 6 of transformer **T^D**, the circuit being through track rail 1^a of section **X^a**—D, wires 58, 59 and 87, resistance 88, wire 89, track rail 1, the wheels and axles of the train, track rail 1^a, wire 90, back contact 63 of relay **F⁶**, wire 64, circuit controller 65 operated by signal **S^D**—**W**, wire 66, circuit controller 67 operated by signal **S^D**—**E**, front contact 68 of relay **H^D**, wires 69 and 70, rail 1 of section **X^a**—D and wire 71 to secondary 6 of transformer **T^D**. It follows that the train will not receive train governing current unless signal **S^D**—**E** is in the proceed or caution position and the circuit for the reset section **X^a**—D is intact.

As the train passes through reset sections **X^a**—D and D—**X^a**, it will receive train governing current from secondaries 6 and 7, respectively, of transformer **T^D**.

I will now assume that when the eastbound train enters section **X^a**—E, signal **S^B** is in the stop position so that the supply of

train governing current to this block is discontinued. The engineman must then acknowledge in order to prevent a stop indication. As the train enters reset section 5 X^3 —B, it will receive train governing energy from transformer T^b , so that if signal S^b indicates stop or caution when the train passes point B, the engineman must again acknowledge in order to prevent a stop indication. If, however, the supply of train 10 governing energy to block B—C is discontinued while an eastbound train is passing through the stretch, then when such train enters westbound reset section C— X^4 , it will 15 not receive train governing energy, and so the train-carried governing apparatus will not be reset and it will, consequently, not be necessary for the engineman to acknowledge upon passing the point X^4 . 20 The operation of the apparatus during the passage of the westbound train will be understood from the foregoing without any detailed explanation. It will be observed that as the westbound train passes through west- 25 bound reset section C— X^4 , relay Q^c will not become closed, and, consequently, this train will always receive train governing current from rail 1^a of this section. When the west- 30 bound train passes through reset section 35 X^3 —B, however, relay Q^b will become closed, so that the supply of train governing current to this section will then depend on traffic conditions in advance of this section, and, therefore, this reset section will not necessitate acknowledgement at point X^3 if the train is proceeding under a stop indication.

It will be understood that absolute permissive signaling alone would require only one (or two) track sections between points 40 A and B, whereas in my present invention two reset sections A— X^2 and X^3 —B are added between these points. This does not change the absolute permissive operation of the signals, however, because all signal 45 circuits formerly controlled by track relays F^1 and F^2 alone will now be controlled also by relays E^a_w and E^b . This applies also to blocks C—D and D—E.

Although I have herein shown and de- 50 scribed only one form of apparatus embodying my invention, it is understood that various changes and modifications may be made therein within the scope of the appended claims without departing from the spirit 55 and scope of my invention.

Having thus described my invention, what I claim is:

1. In combination, a stretch of railway 60 track along which traffic moves in both directions, said stretch being divided into blocks and also into a short eastbound reset section and a short westbound reset section, means operating during the passage of a train in either direction through said stretch to supply train governing current to the rails of 65

each block under the control of traffic conditions in advance of the block, means normally operating to supply train governing current to the rails of each reset section regardless of traffic conditions in advance of 70 such section, means operating while an eastbound train occupies said westbound reset section to discontinue the normal supply of train governing current to such section and to supply train governing current to such section under the control of traffic conditions in advance of 75 the train, and means operating when a westbound train occupies said eastbound reset section to discontinue the normal supply of train governing current to the rails 80 of such section and to supply train governing current to the rails of such section under the control of traffic conditions in advance of the train.

2. In combination, a stretch of railway track along which traffic moves in both directions, said stretch being divided into blocks and also into a short eastbound reset section and a short westbound reset section, means operating during the passage of a train in either direction through said stretch to supply train governing current to the rails of each block under the control of traffic conditions in advance of the block, a normally open relay for each reset section, means for each reset section operating when the associated relay is open to constantly supply train governing current to the rails of the section regardless of traffic conditions, means for closing the relay for the eastbound reset section while such section is occupied by a westbound train but not while it is occupied by an eastbound train, means for closing the relay for the westbound reset section while such section is occupied by an eastbound train but not while it is occupied by a westbound train, and means operating when the relay for either section is closed to discontinue the normal supply of train governing current to the rails of the section and to supply train governing current to the section under the control of traffic conditions in advance of the train then occupying the section.

3. In combination, a stretch of railway track along which traffic moves in both directions and containing an eastbound reset section and a westbound reset section, means operating during the passage of a train in either direction through said stretch to supply train governing current to the rails of the main parts of the stretch in advance of the train under the control of traffic conditions in advance of the train, means operating during the passage of an eastbound train to supply train governing current to said eastbound reset section while the train occupies such section regardless of traffic conditions in advance and to supply train governing current to said westbound reset sec- 115 120 125 130

tion under the control of traffic conditions in advance of such section while the train occupies such section, and means operating while a westbound train passes along said stretch to supply train governing current to said westbound section while the train occupies such section regardless of traffic con-

ditions in advance and to supply train governing current to said eastbound section under the control of traffic conditions in advance while the train occupies such section. 10

In testimony whereof I affix my signature.

HOWARD A. THOMPSON.
